MACHINE FOR SEALING CARTONS
AND THE LIKE

Philip G. Schlemmer, Nanuet, N. Y.

Application April 24, 1951, Serial No. 222,548

19 Claims. (Cl. 53—45)

1

This invention relates to a new and improved machine for folding and sealing the flaps of cartons, such as the conventional corrugated cardboard cartons or cases.

It is an object of the invention to provide a sealing machine of the type described having a platform at the front end upon which an open empty carton may be placed for loading or filling with merchandise. After the filling of the carton, the machine is put into operation, the carton is automatically advanced along the platform and guided into association with means for applying adhesive to the carton flaps. The carton is then guided past folding means which fold the adhesive-treated carton flaps to close the carton, and the carton is then moved between rows of rollers which firmly compress the flaps.

Another object of the invention is the provision of a sealing machine of the type described in which the machine is automatically shut off when the carton is moved between the rollers, and the carton is not advanced between the rollers until the operator loads another carton and sets the machine in operation. Thus each carton is retained under compression until the adhesive has dried sufficiently to seal the carton flaps securely.

Other objects and advantages of the invention will be apparent in the course of the following specification when taken in connection with the accompanying drawings in which:

Fig. 1 is a side elevation of the entire machine;

Fig. 2 is an enlarged detailed side elevation of the loading portion of the machine with parts thereof shown broken away and in section;

Fig. 3 is an enlarged detailed side elevation of the compressing and discharge portion of the machine, with parts thereof shown in section. This view shows the opposite side of the machine than that shown in Figs. 1 and 2;

Fig. 4 is a horizontal section along line 4—4 of Fig. 1;

Fig. 5 is a vertical section along line 5—5 of Fig. 1, with portions thereof broken away for clarity;

Fig. 6 is a perspective view of a pair of gluing units of the machine and the mounting means and operating means therefor;

Fig. 7 is an enlarged, detailed, perspective view of one of the gluing units of the machine;

Fig. 8 is an exploded view of a portion of the gluing unit shown in Fig. 7;

Fig. 9 is a vertical section taken along line 9—9 of Fig. 7;

2

Fig. 10 is a horizontal section taken along line 10—10 of Fig. 7;

Figs. 11 to 15 are partial perspective views showing the progressive and successive operational treatment of a carton as it moves through the machine; and

Figs. 16-18 are schematic views showing the manner in which the cartons moving through the machine control the motors which operate the machine.

The machine comprises a pair of spaced side frames or plates 10 and 11 which extend substantially the entire length of the machine and are aligned with each other. Pairs of vertical support members are secured to the side frames 10 and 11, these support members serving as legs upon which the machine stands. As shown in Fig. 1, the machine has respective front, rear, and central pairs of upright support members 12, 13, and 14. The pairs of support members 13 and 14 extend vertically a substantial distance above the side frames 10 and 11.

As shown in Fig. 2, the side frames 10 and 11 may be channel-shaped, having lateral flanges on their top and bottom ends. The support members 12, 13 and 14 may be in the shape of channel bars.

The top ends of the rear support members 13 are connected by a transverse bar 15, and the top ends of the central support members 14 are similarly connected by a transverse bar 16. The side plates 10 and 11 are rigidly connected in their spaced relationship by a transverse channel bar 17 and a rod 18. The respective rear and central uprights 13 and 14 on each side of the machine are connected by longitudinally-disposed channel bars 19, which in turn are connected by a pair of spaced transverse channel bars 20 which support a motor M₂ and a pair of transverse bars 21 which support a motor M₁.

The machine has two distinct sections which are independently and automatically operable. These sections meet approximately at the center of the machine, so that the machine is operationally divided roughly in half. The front half of the machine includes a section for loading cartons, applying glue to the flaps thereof, and folding the flaps. The rear half of the machine includes a section for compressing the folded cartons until they are properly sealed, and for discharging the cartons from the machine.

Referring to Figs. 2, 4, and 5, in which the front loading and sealing section is shown in detail, it will be seen that a flat horizontal platform 22 such as a wooden board or metal plate

is rigidly and immovably mounted centrally between the side frames 10 and 11. This platform 22 serves to support a carton C which is placed thereon with its bottom side flaps depending as shown in Figs. 5 and 11, the carton C sliding rearwardly on said platform during the gluing operation. To enable cartons of various sizes to be placed thereon with the side flaps depending, the platform 22 is made narrow enough to accommodate standard cartons of small size.

The platform 22 has a pair of depending support legs 23 and 24 rigidly secured thereto. Said support legs 23 and 24 are connected by a pair of longitudinally-extending bars 25 which are fixed to the opposite sides of said support legs. The support leg 23 extends below the bars 25 and is held fixed in the machine frame by transverse rod 18 which connects the side frames 10 and 11. The rear ends of bars 25 rest upon the transverse channel bar 17 of the machine frame.

The rear transverse edge of the platform 22 is tapered, as indicated at 22a in Fig. 4 to enable the bottom side flaps of a carton to be folded upwardly as the carton is moved beyond the platform 22. A platform extension plate 26 is mounted beneath the tapered platform end 22a to support the carton after it has been moved beyond the platform and before it enters the compressing section of the machine. As shown in Fig. 2, the extension plate 26 has a flat base portion rigidly mounted on the bars 25, and an upwardly bent flat rear end 27 which is spaced from the rear of platform 22. The extension also has a central vertical fin or support member 28 which is secured along its top edge to the bottom surface of platform 22. The top edge of said fin 28 has a recessed portion 28a which provides clearance for the folding of the carton flaps as the carton leaves the platform 22.

Drive means are provided for moving a carton along the length of platform 22, said drive means comprising a pair of sprocket chains 30 and 31 which are mounted in the machine frame on opposite sides of the platform 22 and spaced from said platform. Each sprocket chain 30, 31 is trained over respective sprockets 32, 33, and 34. The pair of sprockets 32 are drive sprockets and are both keyed to a shaft 35, the ends of which are journaled in the side frames 10 and 11. The pairs of sprockets 33 and 34 are idler sprockets, the sprockets 34 being rotatably mounted on respective arms 36 which are fixed to the rod 18.

The shaft 35 also carries a fixed sprocket 37, the latter being connected to a sprocket 39 by a sprocket chain 38. Sprocket 39 is keyed to a shaft 40 to which also is keyed a sprocket 43. The shaft 40 is journaled in the side frames 10 and 11, and has an end 40a which extends through and projects laterally from the side frame 11, as shown in Fig. 4. This shaft end 40a has keyed thereto a wheel 42, for a purpose which will be presently explained.

The sprocket 43 is connected by a sprocket chain 44 to a sprocket 45 which is driven by the motor M₁. The motor M₁ may drive said sprocket 45 through a conventional set of reduction gears housed within an integral gear box.

The endless chains 30 and 31 each have respective planar, horizontal, top runs which are designated as 30a and 31a in Figs. 2 and 5. These top runs 30a and 31a are parallel to and substantially horizontally aligned with the top surface of platform 22. The chains 30 and 31 extend through respective cover plates 46 and 47

which bracket the top runs 30a and 31a and thereby guide said top runs in a truly horizontal direction, preventing sagging thereof. As shown in Fig. 5, the cover plates 46 and 47 are secured to the machine frame by posts 51. The sprockets 33 are rotatably mounted on the front ends of the cover plates 46 and 47.

The sprocket chains 30 and 31 carry transverse pusher bars 48 and 49 which are secured at diametrically opposed points on said chains. The bars 48 and 49 are attached to the inner side edges of each chain 30 and 31 by flat extension brackets 50 which are inwardly disposed to permit the bars 48 and 49 to clear the cover plates 46 and 47 as the sprocket chains 30 and 31 are driven.

The drive sprockets 32 are rotated in such a direction that the sprocket chain top runs 30a and 31a move in a rearward direction, the pusher bars 48 and 49 being carried along the top surface of platform 22. Since the sprocket chains move in unison, the bars 48 and 49 are always maintained substantially perpendicular to the longitudinal axis of platform 22. As one of the pusher bars 48 or 49 traverses the platform 22, it thus contacts a carton C resting on the forward end of said platform and pushes the carton along the length of the platform and off the rear end 22a of said platform.

30 A pair of guide rails 55, in the form of angle irons, are located on either side of platform 22 and extend along the length of the latter and its extension 26 for guiding the cartons as they are pushed rearwardly on said platform. As shown in Fig. 4, each guide rail 55 has a pair of spaced elongated slots 58 and 59 which are axially aligned with said rail 55. The guide rails 55 are each coupled to a pair of spaced slide arms 61 and 62 by means of upstanding pins 60 which are mounted on said slide arms and which extend through the respective slots 58 and 59. The slide arms 61 and 62 are turnably connected to the respective side frames 10 and 11 by pivot pins 63.

35 The pairs of slide arms 61 and 62 on each side of the machine are connected by longitudinally-extending bars 64, each of said bars 64 being pivotally connected to a slide arm 61 and a slide arm 62. The forward end of each bar 64 is coupled to a respective terminal extension arm 65 which is in turn pivotally connected to a respective crank 66. Each crank 66 has a hub 66a which is keyed to a transverse shaft 67 journaled in the side frames 10 and 11. As shown in Fig. 4, one end 67a of shaft 67 extends through side frame 10 and projects exteriorly thereof. This end 67a bears a handle 68 which is located to be pivoted manually for turning of the shaft 67.

40 When the shaft 67 is turned, the pair of cranks 66 turn in unison, and move the bars 64 longitudinally, causing the pairs of slide arms 61 and 62 to pivot, which in turn moves the guide rails 55 in opposite directions transversely of the machine. Since the above-described parts on both sides of the machine are identical in size and construction, rotational movement of shaft 67 causes both rails 55 to move simultaneously through the same distance. The rails 55 are originally set equidistant from the central longitudinal axis of platform 22, and it may be noted that this equidistant relationship will be preserved at all times when said rails are moved transversely. Thus, the rails 55 may be manually adjusted to abut the sides of a carton placed upon platform 22 and said rails will hold and guide

the carton in a perfectly centered position on the platform 22.

As shown in Figs. 1 and 4, the central body portion of handle 68 is flat and wide, having an elongated arcuate slot 69 which is concentric with the shaft 67. A bolt 70 which is secured to, and projects laterally from side frame 10 extends through slot 69 and is threaded on its outer end to receive a wing nut 71. The latter may be tightened on bolt 70 to clamp the handle 68 against a sleeve 72 which is mounted on bolt 70 between frame 10 and handle 68, thereby locking handle 68 in selected adjusted position.

Each rail 55 supports an assembly for applying glue to the flaps of a carton automatically as the carton is pushed rearwardly along platform 22. These glue-applying assemblies are located on opposite sides of the machine frame and are movable transversely with their corresponding guide rails 55. Each assembly includes a U-shaped bar member 80 which may have a top terminal reinforcing plate 81. The plates 81 are secured to the undersides of the respective guide rails 55. An elongated vertical bracket 82 is rigidly secured to each U-shaped member 80, as clearly shown in Fig. 6, said bracket having top and bottom lateral flanges 83 and 84 in which a vertical shaft 85 is journaled.

As shown in Fig. 5, the lower arm of each U-shaped member 80 extends slidably through a reinforced slot 78 in the adjacent side frame 10, 11. The upper arm of each U-shaped member 80 rests slidably upon a block 79 which is affixed to the upper flange of the adjacent side frame.

Each rail 55 carries a fixed upstanding post 87 to the upper end of which is secured a gluing unit 86. These units 86 are located directly above their respective guide rails 55 and in a position to apply glue to the upper side flaps of a carton C, as the carton is guided along the platform 22. Identical gluing units 85 are rigidly secured to the lower inner ends of the U-shaped members 80. The units 85 are vertically aligned with the units 86 and are positioned to apply glue to the lower side flaps of the carton C.

Each upstanding post 87 is reinforced by a cross-bar 88 which is secured to the elongated vertical bracket 82.

Each unit 86 is intermittently operated in a manner to be presently described by an operating lever 89 which has at its free end an elongated slot 90. Through said slot 90 extends a pin 92 which is mounted on the end of an arm 91 which is keyed to the top of shaft 85.

The pins 92 are elongated to allow for vertical adjustment of the units 86. Conventional adjustment mechanism may be provided for this purpose, this mechanism being not shown for convenience of illustration.

An arm 93 is also keyed to the bottom end of each vertical shaft 85. The end of each arm 93 is pivotally connected to an operating lever 94 of each lower gluing unit 85. The units 85 are inverted relative to the units 86.

In Figs. 7-10 one of the upper gluing units 86 is shown in detail and will now be described, it being apparent that this description will also apply to the lower gluing units 85 which have a structure identical with that of the units 86.

As shown in Figs. 7 and 10, the unit 86 has a body portion in the form of a generally rectangular block 96 having a rectangular recess 97 at one end. The recess 97 is so disposed as to present an L-shaped cross-sectional configuration to the block 96 and thereby to define a leg 96a and a

shorter perpendicular leg 96b. A slot 98 extends through the shorter leg 96b and is aligned with the forward wall of leg 96a which borders the recess 97. The slot 98 extends from the bottom edge of leg 96b to a point spaced from the top of said leg 96b. Attached within the slot 98 are the ends of a pair of guide plates 99 and 100 whose free outer ends are flared away from each other in order to engage and guide an open carton flap, even though the flap may be bent or inclined. Guide plate 100 may have an integral planar extension 100a which is secured to the forward wall of leg 96a which borders the recess 97, as shown in Figs. 9 and 10, providing a flat surface against which a carton flap can ride.

The forward wall of the leg 96a, bordering the recess 97, has a flat lateral flange 101 at its upper end, as shown in Fig. 9.

The unit 86 also comprises an outer applicator tube 102 which houses a cylindrical inner applicator tube 103, the latter being hollow and having a bottom open end which abuts the bottom inner surface of the outer applicator tube 102. The inner applicator tube 103 has an upper threaded neck 104 which is adapted to be attached to the end of a flexible feed pipe 105 by a lock nut 106. Glue or a similar liquid adhesive is fed through the neck 104 into the hollow body of inner applicator tube 103 by the pipe 105. The inner applicator tube 103 has a plurality of small, spaced holes or perforations 107 arranged in a longitudinal row adjacent the lower end thereof. A pin 108 extends laterally from the tube 103 adjacent the upper end thereof, said pin 108 having a threaded end which is secured to a correspondingly threaded opening in the wall of tube 103.

The outer applicator tube 102 is also cylindrical having an open top end and a closed bottom end. An elongated transverse slot 109 is located adjacent the top end of tube 102. A portion of the lower outer circumferential surface of tube 102 is flattened to provide a planar surface 110. This planar surface 110 contains a longitudinal row of holes or perforations 111 which are spaced the same distance from each other as the perforations 107 in the inner tube 103.

A collar 112 loosely encompasses the upper end of outer tube 102, said collar having a circular hole or opening 113 adjacent its upper end. The collar 112 is integral with the end of operating lever 89.

A block 114 is provided to mount the outer tube 102 rigidly on the block 96. One end surface of said block 114 has an arcuate recessed portion 114a shaped to embrace the outer tube 102. The block 114 also has respective bolt holes located on either side of the recessed portion 114a, said bolt holes receiving respective bolts 115 and 116 whose threaded ends are sized to fit within threaded holes in the flange 101 of block 96.

In assembling the unit 86, the pin 108 is removed from the inner tube 103 and said inner tube 103 is inserted within the outer tube 102, with the bottom edge of inner tube 103 resting upon the closed bottom end of outer tube 102. In this position, the perforations 107 are aligned with the perforations 111, and the slot 109 is aligned with the threaded hole in inner tube 103 which receives pin 108. The outer tube 102 is then placed within the collar 112 with the hole 113 of said collar in registry with the slot 109 of outer tube 102. The pin 108 is then inserted through the aligned hole 113 and slot 109, and is secured to the inner tube 103, said pin thus locking to

gether the inner tube 103, outer tube 102, and collar 112.

In the assembled unit 86, it is apparent that the collar 112 may be rotated or turned relative to the outer tube 102, and that the inner tube 103 will turn in unison as the pin 108 slides within the slot 109. This turning movement enables the perforations 107 to be brought into and out of registry with the aligned perforations 111.

The outer tube 102 is held rigidly in position by inserting the block 114 in place and tightening the bolts 115 and 116, whereby the recessed portion 114a of block 114 embraces the outer wall of tube 102 and clamps the tube 102 tightly against the flange 101 of block 96. The planar surface 110 of outer tube 102 is held parallel to and facing the flat planar extension 100a of plate 100, defining a passageway 117 through which a carton flap can travel for gluing. This passageway 117 is aligned with the slot 98 of block 96.

While the head of bolt 115 may contain the usual slot for the reception of a screw-driver or similar tool, it is preferred to provide the head of bolt 116 with a finger-grip or bar 118 by means of which said bolt may be manually loosened and tightened for vertical adjustment of the outer tube 102.

Referring now to Fig. 1, it may be seen that the flexible feed pipes 105 which are attached to the respective necks 104 of each pair of flap processing units 86 and 95, all communicate with a hollow distributing member 119 which is attached to the spigot 120 of a reservoir 121. The reservoir 121 is filled with glue or other liquid adhesive and is mounted an appreciable distance above the flap processing units 86 and 95 so that the glue is gravity fed to the inner tubes 103 of said units. When the perforations 107 and 111 of said units are in registry, glue will flow through said perforations and into contact with the flaps of cartons moving through the passageways 117.

The reservoir spigot 120 has a valve 122 which is controlled by a handle 123 so that the flow of glue into the feed pipes 105 may be cut off when desired for cleaning, repair, etc.

As shown in Figs. 4 and 6, the end of a respective crank 124 is keyed to each vertical shaft 85. Each crank 124 is arcuate, and is pivotally connected at its other end to a terminal block 126 of a respective connecting rod 125. The other end of each connecting rod 125 also carries a rigid terminal block 127.

A lever 128 is pivotally connected the block 127 of one of the connecting rods 125, the end of said lever 128 being keyed to a shaft 129. As shown in Fig. 4, the shaft 129 extends transversely through respective openings in the side frames 10 and 11. When shaft 129 is turned, the connecting rod 125 is moved longitudinally.

The block 127 of the other connecting rod 125 is pivotally attached to the end of a bell-crank lever 130, the latter being keyed at its center to the end of shaft 129, as shown in Fig. 3. A follower wheel 131 is mounted on the free end of bell-crank lever 130. A spring 132 which is secured to said bell-crank lever 130 and to an arm 133 rigidly mounted on the machine frame, urges said bell-crank lever 130 to the position in Fig. 3 in which the follower wheel 131 abuts the periphery of the wheel 42 which is keyed to the end of shaft 40.

A cam plate 134 is secured to the edge of wheel 42 and extends beyond the periphery of said wheel 42. When the wheel 42 is rotated, this cam plate 134 comes in contact with follower wheel

131 and raises said wheel 131, as shown in broken line in Fig. 3, causing the bell crank lever 130 and shaft 129 to turn, which in turn moves the connecting rods 125 forwardly in a longitudinal direction, causing each operating lever 89 to turn its integral collar 112. Thus each inner tube 103 is turned until its perforations 107 are in registry with the perforations 111 of the outer tube 110. All of the flap processing units 86 and 95 are therefore simultaneously brought into operative position. When the cam plate 134 passes the follower wheel 131, the spring 132 brings said follower wheel 131 back into contact with the peripheral surface of wheel 42, thus pivoting bell-crank lever 130 in the opposite direction, which immediately brings the flap processing units 86 and 95 to their inoperative position in which the perforations 107 and 111 are out of registry.

It is apparent that the width of the cam plate 134 determines the length of time for which the units 86 and 95 are maintained in their operative positions. The cam plate 134 is mounted for synchronous cooperation with the transverse pusher bars 48 and 49 which connect the chain belts 30 and 31, so that the units 86 and 95 are opened only during the time that the flaps of a carton are passing said units. The length of the cam plate 134. For this reason, the cam plate 30 is preferably removably secured to wheel 42 as by screws 135, so that it may be replaced for cartons of varied sizes.

It may also be noted that if it is intended to apply glue only to the front and rear ends of the carton flap, but not at the center thereof, as is sometimes desirable, the large cam plate 134 may be replaced by a pair of narrower cam plates suitably located for this purpose.

The threaded upper end 140a of a vertical cylindrical shaft 140 extends through an opening in the center of the transverse bar 16 which connects the central vertical support members 14 of the machine frame. In a similar manner, the threaded upper end 141a of a shaft 141 extends through an opening in the center of transverse bar 15 which connects the rear vertical support members 13. As shown in Fig. 3, each shaft 140 and 141 is supported by a respective sleeve 142 and 143, each of said sleeves bearing a respective sprocket 144 and 145. The sleeves 142 and 143 are threaded and act as nuts on the threaded ends of shafts 140 and 141. The sprockets 144 and 145 are connected by and mesh with, a chain belt 146. The sleeve 143 has a hand grip 147 by means of which said sleeve 143 may be rotated manually.

The shafts 140 and 141 extend through respective transverse flat bars 148 and 149 which bridge the side frames 10 and 11. These transverse bars 148 and 149 rest upon, and are supported by enlarged terminal heads 150 and 151 of the shafts 140 and 141. Longitudinal channel bars 152 and 153, which are located on opposite sides of the machine frame are secured to the lower surface of both transverse bars 148 and 149, and are carried thereby. As shown in Fig. 1, the longitudinal channel bars 152 and 153 have guide wheels 154 and 155 on their outer faces, said guide wheels 154 and 155 respectively abutting the facing vertical edges of the uprights 13 and 14. Guide wheels 154 and 155 maintain the longitudinal channel bars 152 and 153 in a horizontal position parallel to the platform 22.

A flat transverse bar 158 is secured across the tops of the channel bars 152 and 153, forwardly

of the transverse bar 148. At the center of the bar 158 is mounted a pair of upstanding posts 159 which support a platform 160. The glue reservoir 121 rests upon said platform 160.

The closed end of a bracket 161 is mounted on the cylindrical shaft 140, said bracket 161 extending in a longitudinal direction toward the forward end of the machine and having flat, spaced parallel side arms between which a flat flap-folding arm 162 is slidably mounted. As shown in Fig. 2, the bracket 161 rests upon the two transverse bars 148 and 158. The flap-folding arm 162 has a slot 163 which is adjacent and parallel to its top longitudinal edge. A pair of bolts 164 which extend through the arms of bracket 161, also extend through the slot 163, so that the flap-folding arm 162 may be slid in a longitudinal horizontal direction relative to the bracket 161. An end-stop 165 located at the rear end of the slot 163 limits the forward movement of the arm 162 to an extended position in which its front edge is substantially vertically-aligned with the front edge of the platform 22.

As shown in Fig. 2, the flap-folding arm 162 has a bottom longitudinal edge which is parallel to the top surface of platform 22, and which has a forward recessed portion 166. The arm 162 also has an operating handle 167 for manually sliding said arm 162.

As shown in Figs. 2 and 5, a pair of inclined folding rods 168 and 169 are respectively secured at one end to opposed points on the respective side frames 10 and 11. The rods 168 and 169 are inclined upwardly and inwardly, the free ends thereof converging between the rear end 22a of platform 22 and the rear end 27 of platform extension 26. A similar pair of folding rods 170 and 171 are mounted above the rods 168 and 169, the ends of said rods 170 and 171 being respectively secured to the longitudinal channel bars 152 and 153. The rods 170 and 171 are inclined downwardly and inwardly, their free ends converging above the free ends of rods 168 and 169. The pair of arms 168 and 169 serve to fold up the bottom side flaps of a carton after glue has been applied thereto, while the pair of arms 170 and 171 serve to fold down the top side flaps of the carton.

A plate 172 is rigidly mounted beneath bar 158 by a pair of depending posts 173, said plate 172 being located centrally in the machine frame directly to the rear of the converging ends of rods 170 and 171. As shown in Figs. 2 and 5, plate 172 has a forward, upwardly bent portion 172a which contains a central slot 174 in order to provide clearance for the rearward sliding of the flap-folding arm 162.

A lever 175 is pivoted to the machine frame adjacent the forward end of platform 22. This lever 175 is connected by a rod 176 to the operating arm 177 of a switch SW₁, as shown in Figs. 1, 3, 4, and 16. The switch SW₁ operatively controls the motor M₁ in such a manner that when the lever 175 is pivoted toward the forward end of the machine, the motor M₁ is actuated. As shown in Fig. 4, the switch SW₁ is located adjacent the side frame 10 with its operating arm 177 located proximate to the top run 30a of chain belt 30, and in a position to be engaged and pivoted rearwardly by one of the pusher bars 48 or 49, thus de-actuating the motor M₁.

As shown in Figs. 2, 3, and 5, a pair of channels 178 and 183 are mounted inwardly of the respective longitudinal channel bars 152 and 153 by connecting posts 180. The channels 178 extend

longitudinally along the entire rear half of the machine, and have mounted therebetween a row of closely-spaced idler rollers 181.

As shown in Figs. 1, 2, and 3, the side frames 10 and 11 respectively carry similar channels 182 and 183, between which are mounted rollers 184. The rollers 184 are also closely spaced. An endless belt 185 is trained over the top surfaces of the rollers 184, said belt 185 being driven by a drive roller 186 and tensioned by an idler roller 187. The drive roller 186 is mounted adjacent the rear ends of channels 182 and 183, and is rotated by a chain belt 188 connected to a sprocket wheel 189 of a motor M₂ which is mounted on the transverse channel member 20 of the machine frame.

The idler roller 187 is mounted on a shaft 190 which is supported by an upright rod 191, as shown in Fig. 3. The rod 191 has a threaded lower end which fits through a hole in the bottom flange of side frame 10. This hole is bracketed by a pair of nuts 192 through which the threaded end of rod 191 also extends. The rod 191 may be turned relative to the nuts 192 to raise or lower said rod 191 and thus vary the tension of idler roller 187 upon the belt 185.

The rows of rollers 181 and 184 are of substantially equal length and are aligned with each other. The top surfaces of the rollers 184 are on the same horizontal level as the top surface of platform 22, as is also the top horizontal run of the endless belt 185 which traverses these rollers 184.

Each roller 184 and 185 is so closely spaced from the adjacent rollers in its row that a substantial area at the top and bottom of a carton C, which is moved between the row of rollers, is always in contact with the rollers. Each roller 184 and 185 is preferably spaced one to two inches or even less from the next adjacent rollers in its row.

The rear ends of the channels 178 and 179 and 182, 183 which carry the respective rollers 181 and 184, project rearwardly beyond the end of the machine frame and are open at this projecting end to define a discharge opening 193 for the cartons after they are processed.

Actuation of the motor M₂ is controlled by a switch SW₂ which has a mounting bracket 194. The bracket 194 is mounted on the cylindrical shaft 140 above the flat transverse bar 148 as shown in Fig. 3. The switch SW₂ has an operating lever 195 which is operatively coupled by a connecting rod 196 to the end of a trip lever 197. The trip lever 197 is pivoted adjacent its center to an extension of the transverse flat bar 158 which bridges the longitudinal channel bars 152 and 153. A spring 199 normally maintains the trip lever 197 in its inoperative position of Figs. 3 and 18, in which the switch SW₂ is in its "off" position and the motor M₂ is not operated.

The free end 197a of trip lever 197 is located forwardly of the row of rollers 181 and on a level slightly below the bottom surfaces of the rollers 181. This free end 197a is thus in a position to be engaged by a carton passing from the platform 22 to the rollers 181 and 184, causing the trip lever 197 to pivot to its operative position of Fig. 17 in which it brings the switch SW₂ to its "on" position and causes the motor M₂ to be actuated. After the carton has cleared the trip lever 197, the spring 199 returns said trip lever to its inoperative position.

The drawings are substantially to scale and reference is made thereto for further disclosure.

11

Operation

The machine requires the provision of an operator for manually performing the initial operational steps. The operator, standing at the forward end of the machine, takes an empty carton C, folds in its bottom end flaps E, as shown in Fig. 11 and places the carton upon the forward end of platform 22. In this position of carton C, the bottom side flaps B are extending vertically downward below the platform 22, and the top side flaps S and top end flaps T are extending vertically upward. The operator may then fill the carton C with boxes, bottles, jars, or the like through the open top end of said carton.

At any convenient time before or after the loading of the first carton C, the machine may be adjusted to conform to the dimensions of the cartons. For this purpose, the handle 68 is pivoted until the guide rails abut the sides of the carton C, and the handle 68 is then locked in this adjusted position by the wing nut 71. The longitudinal channel bars 152 and 153 are then adjusted vertically by turning the hand grip 147 of the sleeve 143 until the vertical distance between the rows of rollers 181 and 184 conforms to the height of the carton C.

It is to be noted that during this vertical adjustment when the channel bars 152 and 153 are raised or lowered, they carry with them the flap-folding arm 162, upper gluing units 86, upper folding rods 170 and 171, plate 172, and the trip lever 197 of switch SW2, bringing the latter members automatically to their proper positions for processing the carton C.

After the carton C has been suitably loaded or filled, the operator grasps the operating handle 161 of the flap-folding arm 162 and slides said arm 162 to its furthest forward position, as shown in Figs. 2 and 12. This action causes the recessed portion 166 of said arm 162 to fold down and hold the top end flaps T of carton C. The operator then pulls the lever 175 at the front of the machine, and the remaining processing steps of the carton are then automatically performed.

Actuation of the lever 175 pivots the operating arm 177 of switch SW1 to its "on" position, closing said switch and actuating the motor M₁. As the motor M₁ is operated, the chain belts 30 and 31 are rotated in the direction of the arrows in Fig. 16, causing one of the pusher bars 48 to traverse the top surface of platform 22. The pusher bar 48 engages the carton C on platform 22 and pushes said carton C from the front to the rear of said platform.

In the course of its travel along platform 22, the carton C encounters the gluing units 86 and 95, the upper side flaps S of said carton C being guided by the guide plates 99 and 100 of the upper gluing units 86 through the passageways 117 of said units 86. Similarly, the lower side flaps B of carton C are guided through the respective passageways 117 of the lower gluing units 95.

As the carton side flaps enter the passageways 117, the cam plate 134 of the rotating wheel 42 is turned into contact with the follower wheel 131 of bell-crank lever 130, pivoting said bell-crank lever and thereby moving the connecting rods 125 longitudinally. This movement of the connecting rods 125 simultaneously turns the inner applicator tubes 103 of all of the gluing units 86 and 95 until the row of perforations 107 of each inner applicator tube 103 is in registry with the row of perforations 111 of the respective outer applicator tube 102. As the upper and

12

lower side flaps S and B of the carton C are carried through the passageways 117 of the respective gluing units 86 and 95, spaced lines of glue are applied along the entire inner surface of said flaps, as shown in Fig. 13.

As soon as the carton flaps S and B move out of contact with the gluing units 86 and 95, the cam plate 134 is turned out of contact with the bell-crank lever 130, enabling the spring 132 to urge said bell-crank lever 130 to its inoperative position in which the follower wheel 131 abuts the periphery of wheel 42, and the gluing units 86 and 95 are closed.

The carton C is then carried along platform 22 by pusher bar 48 until it reaches the tapered rear end 22a of said platform. In this position, the top side carton flaps S are engaged by the upper folding rods 170 and 171 and are folded downwardly, as shown in Fig. 14, while simultaneously the bottom side flaps B are folded upwardly by the lower folding rods 168 and 169. The tapered end 22a of platform 22 provides clearance to enable the bottom side flaps B to begin to be folded upwardly as the carton C leaves the platform 22.

When the carton C leaves the platform 22, it is supported by the platform extension 26 which also maintains the bottom side flaps B closed. Similarly, the top side flaps S of the carton C are maintained closed by the plate 172.

As the carton C is pushed off the platform 22, the front of said carton engages the free end 197a of trip lever 197, and pivots said trip lever to close the switch SW2. The motor M₂ is thereby actuated, rotating the endless belt 185 which carries the carton C between the rows of rollers 181 and 184. At the same time, the pusher rod 48 comes in contact with the operating arm 177 of switch SW1, pivoting said operating arm 177 rearwardly and opening switch SW1. The motor M₁ is thus de-actuated.

When the carton C has been moved entirely between the rows of rollers 181 and 184, as shown in Figs. 3 and 18, it clears the trip lever 197, permitting the spring 199 to pivot said trip lever 197 and open switch SW2. The motor M₂ is thereby de-actuated and the endless belt 185 ceases its movement. At this stage, neither motor M₁ or M₂ is operating, and the machine is motionless.

The operator may then place another empty carton on platform 22, fill this carton, and perform the same initial operational steps, finally pulling the lever 175 to set the motor M₁ in operation. When this second carton closes the switch SW2, the first carton is advanced between the rows of rollers 181 and 184, until the second carton clears the trip lever 197 of switch SW2, at which time both cartons are located between the rows of rollers 181 and 184, and remain in this position until a third carton closes the switch SW2.

Thus each carton is brought between the rows of rollers 181 and 184 and is not advanced therein until a succeeding carton is loaded and sent along the platform 22. As each carton is brought between the rollers 181 and 184, the preceding cartons are moved along only through a distance approximately equal to the length of a carton. The cartons are therefore retained between the rows of rollers 181 and 184 for a relatively long operational time. The rollers 181 and 184 are spaced vertically a sufficient distance to compress the cartons firmly therebetween, so that

the top and bottom side flaps will seal tightly and securely.

When each carton traverses the length of the rows of rollers 181 and 184, it is ejected from the discharge opening 193 on to a suitable platform, chute, container, or the like.

While a preferred embodiment of the invention has been shown and described herein, it is obvious that numerous omissions, changes, and additions may be made without departing from the spirit and scope thereof.

What is claimed is:

1. A machine for sealing cartons which have overlapping flaps, said machine comprising a reservoir for liquid adhesive, a plurality of gravity-fed hollow applicator units communicating with said reservoir and each having a vertically-disposed row of spaced adhesive outlet openings, means for moving cartons in succession past said applicator units with some of the carton flaps open and vertically disposed, means to guide some of the open and vertically disposed flaps of each carton simultaneously into a slidably abutting association with the respective vertical rows of outlet openings of said applicator units as the carton is moved past said limits, automatic means to operate each applicator unit simultaneously when the carton flaps are in abutment with the outlet openings thereof in order to apply adhesive to said flap through said outlet openings in spaced parallel lines, and to close each applicator unit when the carton flaps have moved out of contact with said applicator units, means to fold said carton flaps after the application of adhesive thereto, and compression means to compress said flaps after the folding thereof.

2. A machine for sealing cartons which have top and bottom closure flaps, said machine comprising a frame having a front loading opening and a rear discharge opening, a loading platform within said frame extending longitudinally from said front loading opening toward said rear discharge opening, said platform being of sufficient width to support a carton thereon with the top side flaps of the carton upstanding and the bottom side flaps of the carton depending below said platform, means to push said carton along said platform to the rear end thereof with the side carton flaps extended vertically, a reservoir for liquid adhesive mounted above said platform, a plurality of gravity-fed applicator units located below said reservoir, each applicator unit being hollow and having an inlet opening communicating with said reservoir, a vertical row of spaced outlet openings and closure means for said outlet openings, said applicator units being located above and below said platform and each being positioned to slidably abut an extended side flap of said carton when said carton is moved along said platform past said units, automatic means to simultaneously open the applicator unit closure means when said carton flaps are in abutment with said applicator units in order to apply adhesive through each row of openings to each respective carton flap in spaced parallel lines, and means to close each closure means when said carton flaps have moved past said applicator units, means to fold said side carton flaps in overlapping relation to the end flaps of said carton after the application of adhesive to said side flaps, and means to compress said folded flaps, said compression means being located between the folding means and the rear discharge end of the machine.

3. A machine for sealing cartons which have top and bottom closure flaps, said machine comprising a frame having a front loading opening and a rear discharge opening, a loading platform within said frame extending longitudinally from said front loading opening toward said rear discharge opening, said platform being of sufficient width to support a carton thereon with the top side flaps of said carton upstanding and the bottom side flaps of the carton depending below said platform, means to push said carton longitudinally along said platform to the rear end thereof, a pair of guide bars located on opposite sides of the platform and parallel thereto, said guide bars being spaced to abut the side walls of a carton and thereby to guide said carton along said platform, a reservoir for liquid adhesive mounted above said platform, a plurality of gravity-fed applicator units located below said reservoir, each applicator unit being hollow and having an inlet opening communicating with said reservoir, a row of spaced outlet openings, and closure means for said outlet opening, said applicator units being located above and below said platform and each being positioned to slidably abut a side flap of said carton when said carton is moved along said platform past said units, automatic means to simultaneously open the applicator unit closure means when said carton flaps are in abutment with said applicator units and to close each closure means when said carton flaps have moved past said applicator units, means to fold said side carton flaps in overlapping relation to the end flaps of the carton, said folding means being spaced rearwardly of said platform, means to compress said folded flaps, said compression means being located rearwardly of said folding means and extending to the rear discharge opening of said frame, and independent drive means to advance the cartons in succession through said compression means as each subsequent carton is moved to the rear end of said platform.

4. A machine according to claim 3 in which a plurality of movable arms are pivotally mounted on opposite sides of the machine frame, said guide bars having elongated longitudinal slots, said arms having terminal pins which extend through said slots, said arms being of equal size and arranged to move said guide bars simultaneously and to the same degree transversely relative to said platform when said arms are pivoted, said guide bars being held by said arms equidistant from and parallel to said platform.

5. A machine for sealing cartons which have top and bottom closure flaps, said machine comprising a frame having a front loading opening and a rear discharge opening, a horizontal platform extending from the front loading opening interiorly of said frame, a reservoir for liquid adhesive, a plurality of applicator units fed by said reservoir and arranged adjacent said platform in a position to apply adhesive to said carton flaps, folding means located adjacent said platform to fold said carton flaps after the application of adhesive thereto, and a pair of vertically-spaced upper and lower row of compression rollers located rearwardly of said platform and extending through the interior of the machine frame to said rear discharge opening, said rows of rollers being spaced a sufficient distance from each other to receive a carton therebetween and to compress the folded flaps thereof, a pair of endless chain belts mounted on opposite sides of said platform, said chain belts having respective

15

top runs which are aligned with the top surface of said platform, at least one transverse bar joining said chain belts and being positioned to traverse the top surface of said platform when said chain belts are turned, motor driven means to turn said chain belts in unison whereby to cause said bar to push a carton along said platform from the front end to the rear end thereof and past said applicator units and folding means to said rows of compression rollers, motor-driven advancing means to advance cartons between said rollers to said discharge opening, said advancing means being operable when a carton is moved out of contact with the platform and into contact with the compression rollers, to cause the cartons between said rows of rollers to advance a distance substantially equal to the length of one carton.

6. A machine according to claim 5 in which the advancing means is controlled by a switch, said switch having an operating lever located at the forward end of said rows of rollers in a position to be operatively engaged by a carton moving into contact with said rollers, said operating lever when operatively engaged actuating said advancing means, said operating lever deactuating said advancing means when said carton has moved between said rows of rollers and out of operative engagement with said operating lever.

7. A machine according to claim 6 in which said motor-driven means to turn said chain belts is controlled by a switch having a pivotable operating arm located at the rear end of the top runs of said chains and positioned to be engaged by said transverse bar and to be pivoted to inoperative position thereby, said operating arm having manual means for pivoting it to operative position in which it actuates said motor-driven means.

8. A machine for sealing cartons with top and bottom closure flaps, said machine comprising a frame having a front loading opening and a rear discharge opening, a horizontal platform extending from the front loading opening interiorly of said frame, a reservoir for liquid adhesive, a plurality of applicator units gravity-fed by said reservoir and arranged adjacent said platform in a position to apply adhesive to said carton flaps, means to fold said flaps after the application of adhesive thereto, means to compress said folded flaps, and motor-driven means to move a carton rearwardly along said platform, said motor driven means including a wheel which is rotated thereby, said wheel having a cam plate projecting from its periphery, each of said applicator units comprising an outer tube and an inner tube, each of said tubes having a row of perforations in alignment with each other, said inner tube being turnable in said outer tube to bring said rows of perforations into and out of registry with each other, the turning movement of each inner tube being controlled by a single lever pivotally mounted on the machine frame and having a free end which rides upon the periphery of said wheel, said cam plate being positioned to turn into contact with and raise the free end of said lever to bring said rows of perforations into registry, said cam plate being positioned to raise the free end of said lever when the carton flaps are in contact with their respective applicator units.

9. A machine for sealing cartons which have overlapping flaps, said machine comprising a frame having a front loading opening and a rear discharge opening, a horizontal platform extending from the front loading opening interiorly of said frame, said platform being sized throughout

16

its length to support a carton thereon with the side flaps thereof extended and having a front end accessible from the front end of said machine for manual filling of said carton, means to push said carton rearwardly along the length of said platform, an actuating member accessible from the front of said machine for setting said pushing means in operation, means to apply adhesive to the extended flaps of said carton, means to fold said flaps after the application of adhesive thereto, a pair vertically spaced rows of compression rollers extending from the rear end of said platform to said rear discharge opening and positioned to receive the carton therebetween when the carton reaches the end of said platform, drive means for said compression rollers, and automatic means for deactuating said pushing means and actuating said drive means when the carton is received by said rollers.

10. A machine according to claim 9 in which said rows of compression rollers are long enough to receive therebetween a plurality of cartons, said compression roller drive means being operable to advance the cartons between said rollers by a distance equal to the length of one carton when a carton is pushed to the rear end of said platform.

11. A machine according to claim 10 in which said drive means including switch means are positioned to be actuated by contact with the carton as it reaches the end of said platform.

12. A machine for sealing cartons which have top and bottom closure flaps, said machine comprising a frame having a front loading opening and a rear discharge opening, a horizontal platform extending from the front loading opening interiorly of said frame, said platform being sized throughout its length to support a carton thereupon with its top side flaps upstanding and its bottom side flaps depending and having a front end accessible from the front end of said machine for manual filling of said carton, a pusher bar located to traverse the top surface of said platform to push the carton therealong, drive means for moving said pusher bar from the front of said platform to the rear thereof, manually-operable control means at the front of said machine for actuating said drive means, means for applying adhesive to the extended carton side flaps as the carton is pushed along said platform, means to fold said extended flaps after the application of adhesive thereto, a pair of rows of horizontally-spaced compression rollers extending from the rear end of said platform to said rear discharge opening and positioned to receive a carton therebetween when the carton reaches the end of said platform, drive means for at least one row of compression rollers, and automatic switch means for deactuating said pusher bar drive means and actuating said compression roller drive means when the carton is received by said rollers.

13. A machine for sealing cartons which have overlapping flaps, said machine comprising a reservoir for liquid adhesive, a plurality of gravity-fed applicator units communicating with said reservoir, means for moving cartons in succession past said applicator units with some of their flaps open and vertically disposed, means to guide some of the open flaps of each carton into operative association with said applicator units, means to fold said carton flaps after the application of adhesive thereto, and means to compress said flaps after the folding thereof, each of said applicator units comprising an outer member

having a flat applicator surface containing a longitudinal row of spaced outlet openings, an inner tube turnably contained in said outer member and having a row of outlet apertures positioned to register with the outlet apertures of said outer member, said inner tube having an inlet opening communicating with said adhesive reservoir, said applicator unit also including a mount having a planar guide surface, said applicator unit being fixed to said mount with the outer member applicator surface facing said guide surface and being spaced therefrom a sufficient distance to enable a carton flap to pass therethrough in slideable contact with both said surfaces, said mount also having guide means to receive said carton flap and guide it between said surfaces, said machine also having automatic means to bring said rows of outlet openings into registry when said carton flap is passing transversely thereby.

14. A machine for sealing cartons which have overlapping flaps, said machine comprising a reservoir for liquid adhesive, a plurality of gravity-fed applicator units communicating with said reservoir, means for moving cartons in succession past said applicator units with some of their flaps open and vertically disposed, means to guide the open flaps of each carton into operative association with said applicator units, means to fold said carton flaps after the application of adhesive thereto, and means to compress said flaps after the folding thereof, each of said applicator units comprising an outer member having a flat applicator surface containing a row of spaced outlet openings, an inner cylindrical tube turnably contained in said outer member and having a row of outlet apertures positioned to register with the outlet apertures of said outer member, said inner tube also having an inlet opening communicating with said adhesive reservoir, said applicator unit also including a casing having a passageway, said outer member being mounted on said casing with its applicator surface in registry with one side of said passageway, said passageway being sized to enable a carton flap to pass therethrough and hold said carton flap in slideable contact with said applicator surface as said flap moves transversely past said row of outlet openings, said casing having a pair of outwardly-flared plates leading to said passageway and positioned to receive said carton flap and guide it into said passageway, said machine also having automatic means to bring said rows of outlet openings into registry when said carton flap is passing thereby.

15. A machine according to claim 14 in which said outer member is cylindrical and contains a slot extending around a portion of its circumference, said inner tube containing a pin which extends through said slot, said applicator unit having a collar embracing said outer member and turnable thereon, said pin extending through a hole in said collar, said collar having an extension arm, said automatic means being adapted to reciprocate said extension arm to reciprocally turn said collar and inner tube, the limits of the movement thereof being limited by the travel of said pin within the length of said slot.

16. A machine according to claim 15 in which said row of outlet apertures are in registry when the pin is at one end of said slot.

17. A machine for sealing cartons which have overlapping flaps, said machine comprising a frame, a fixed platform extending longitudinally through said frame and sized to support a carton

with its top and bottom side flaps open and extended, means to move said carton longitudinally along said platform, means to apply adhesive to the extended side flaps of said carton, means to fold said carton flaps, means to compress said folded carton flaps, and means to guide said moving carton along said platform into successive operative association with said adhesive-applying means, folding means, and compression means, said guide means comprising a pair of spaced guide bars located parallel to and on opposite sides of said platform and each having elongated slots therein, a plurality of movable arms pivotally mounted on opposite sides of the machine frame and having respective terminal pins which extend through said slots, said arms being of equal size and arranged to move said guide bars simultaneously and to the same degree transversely relative to said platform when said arms are pivoted, said guide bars being held by said arms equidistant from and parallel to said platform.

18. A machine according to claim 17 in which a manually-operable member is mounted on said machine frame and connected to said movable arms for pivoting all of said arms in unison.

19. A machine for sealing cartons which have top and bottom closure flaps, said machine comprising a frame having a front loading opening and a rear discharge opening, a loading platform within said frame extending longitudinally from said front loading opening toward said rear discharge opening, said platform being of sufficient width to support a carton thereon with the top side flaps of said carton upstanding and the bottom side flaps of the carton depending below said platform, means to push said carton longitudinally along said platform to the rear end thereof, a pair of guide bars located on opposite sides of the platform and parallel thereto, said guide bars being spaced to abut the side walls of a carton and thereby to guide said carton along said platform, a reservoir for liquid adhesive mounted above said platform, a plurality of gravity-fed applicator units located below said reservoir, each applicator unit being hollow and having an inlet opening communicating with said reservoir, at least one outlet opening, and closure means for said outlet opening, said applicator units being located above and below said platform and each being positioned to slidably abut a side flap of said carton when said carton is moved along said platform past said units, automatic means to simultaneously open the applicator unit closure means when said carton flaps are in abutment with said applicator units and to close each closure means when said carton flaps have moved past said applicator units, means to fold said side carton flaps in overlapping relation to the end flaps of the carton, said folding means being spaced rearwardly of said platform, means to compress said folded flaps including a pair of rows of transverse rollers arranged longitudinally of the machine and in vertical alignment with each other, said rollers being spaced vertically from each other, means to vertically adjust the top row of rollers as a unit relative to the bottom row of rollers whereby to space said rows of rollers a sufficient distance to compress a carton therebetween, an endless belt trained over the lower row of rollers, motor-driven means for turning said belt, and switch means positioned to be operatively engaged by a carton moving to the rear end of said platform, said switch means being operatively

connected to said motor-driven means and adapted to actuate said motor when said switch means is operatively engaged by said carton and to de-actuate said motor when said carton has moved past said switch means, said endless belt when turned being adapted to advance all of the cartons contained between the rows of rollers, said switch means being located sufficiently close to the forward end of said rows of rollers to enable substantially the entire length of a carton 19 to be positioned between the rows of rollers at the instant that the carton passes out of operative contact with said switch means.
